UNITED STATES PATENT OFFICE.

CLARK S. EATON, OF PARK RIVER, NORTH DAKOTA.

GRAIN-CAR DOOR.

1,204,962.

Specification of Letters Patent. Patented Nov. 14, 1916.

Application filed May 11, 1914. Serial No. 837,822.

To all whom it may concern:

Be it known that I, CLARK S. EATON, a citizen of the United States, residing at Park River, in the county of Walsh, State 5 of North Dakota, have invented certain new and useful Improvements in Grain-Car Doors; and I do hereby declare the following to be a full, clear, and exact description of the invention, such as will enable others 10 skilled in the art to which it appertains to make and use the same.

This invention relates to grain cars and has special reference to an improved grain car door.

15 The principal object of the invention is to provide an improved grain car door which may be readily swung into and out of position as required and which, when not in use, may be securely stowed beneath the roof 20 of the car.

Another object of the invention is to provide a flexible grain car door so arranged that it is necessary to stow but one section beneath the roof of the car.

25 A third object of the invention is to provide an improved form of supporting device for the movable sections.

With the above and other objects of similar nature in view the invention consists in 30 the construction, combination and arrangement of parts set forth in and falling within the scope of the appended claim.

Referring now to the accompanying drawings in which like characters of reference 35 designate similar parts in the several views, Figure 1 is an elevation from the inside of a car with the door in position therein, the movable door being partially raised. Fig. 2 is a section on the line 2—2 of Fig. 1 with 40 the movable door in its raised position. Fig. 3 is an enlarged detail section on the line 3—3 of Fig. 1. Fig. 4 is a detail section on the line 4—4 of Fig. 1, the central part of the door being broken away. Fig. 5 is a detail 45 tail side elevation of the pivoted holding device used herewith. Fig. 6 is a detail section on the line 6—6 of Fig. 1, the section showing certain clamping devices used herewith.

50 The grain car herein illustrated is of the ordinary construction so far as its framing and general structure is concerned and is provided with the usual door posts 10 on each side of the door opening 11. These 55 door posts are connected at the top by the lintel 12. Secured to each of these door

posts is a guide member 13 which is preferably formed from sheet metal so bent as to provide a slot 14. At the upper end of each of these guide members 13 the inner side of the member is cut away to provide an opening 15. Fixed to the lintel 12 are plates 16 from which depend the bars 17 provided with laterally extending pivot arms 18. On these arms 18 are mounted the 60 clamps. Each of these clamps consists of a pair of members 19 which are in general form like a pair of tongs, the members passing each other at the pivot point. The lower ends of these members have jaws 20 65 the under surfaces of which are beveled so that any object may be pushed between the jaws provided it is of suitable size, without making it necessary to manually open said jaws. One of the arms of these tongs is bifurcated as at 22 and journaled in the bifurcated portion is a bar 23 from which extends a tongue 24 which passes through a suitable opening in the opposite arm. This tongue 24 is furthermore surrounded by a 70 coil spring 25 which thus serves to hold the arms apart and the jaws together under ordinary circumstances. Extending up from one of the arms of the tongs is a grip 75 or handle 26 and a similar grip or handle 27 is made on the other of the arms. Slidably mounted in the guides 13 is a door 28 which is provided on its upper edge with certain V-shaped blocks 29, these blocks being of such size and shape as to be readily 80 received between the jaws 21 when the door is raised. Within the car, beneath the roof thereof, are blocks 30 whereon are pivoted ordinary turn buttons 31 so arranged as to engage the lower edge of the door when the 85 latter is swung up against the roof on the pivot 18 after being raised.

In order to wedge the door tightly into position there are provided a pair of wedge strips 32 which are pivoted adjacent the 90 lower corners of the door as at 33. These strips are limited in downward movement by stops 34 and are wedge shaped in cross section so that when swung into vertical position the wedge like edges of the strip 95 will enter between the door and the outside of the guide member thus wedging the door firmly into position. In order to hold these strips locked into wedging position a keeper 35 is provided adjacent each upper corner 100 of the door and in this keeper slides a bolt 36 which is provided with spaced stops 37

so that the bolt may be raised as the wedge strip 32 is swung past it and then be dropped behind the wedge strip and lock it in position.

- 5 Adjacent one edge of the door opening are certain plates 38 which carry upstanding pintles 39. On these pintles 39 are supported hinge plates 40 whereto are hinged other plates 41 having suitable slots 42 therein. These slots 42 are arranged, when the hinge is in one position, to engage over staples 43 in the door posts 10. Opposite the staples 43 are other staples 44 which are engaged by hasps 45. The hinge plates 41 are connected to respective door sections 46 and these sections in turn carry the hasps 45. Tapered keys 47 serve to force the door sections 46 firmly against the door posts 10 when the doors are closed. Fixed to one of 20 the meeting edges of the door sections is a channel member 48 wherein is held a wooden strip 49 to the edge of which is secured a piece of cloth or felt 50 so that when the door sections are together grain will 25 be prevented from passing between said sections. Secured centrally of the lower edge of the door 28 is a lifting lug 51 so that a lever may be employed to start the door upward.
- 30 The device is shown in Fig. 1 in the position which the parts assume either just prior to closing all of the doors for the reception of grain or just after the lower door has been removed for withdrawing grain 35 from the body. It is preferable however to first of all drop the section 28 and to do this the buttons under the roof are turned so that the section swings down ready to pass down through the guides. Then the members 40 26 and 27 are grabbed and the doors 21 separated manually. This lets the door 28 drop to the bottom whereupon the members 32 are turned upward, the bolts 36 being lifted, and the door pushed firmly into

place. Then these bolts 36 are dropped so 45 that the door is locked from movement. The remaining door sections 46 may then be swung around from their position of stowage, this being flat back against the side of the car, into position shown in Fig. 1. 50 If the car is loaded from an elevator this may all be done before loading begins while if the car is loaded by hand these sections may be successively swung into place. It is obvious that the reverse of this operation 55 will open the door.

There has thus been provided a simple and efficient device of the kind described and of the character specified.

It will be obvious that many minor 60 changes may be made in the form and construction of this invention without departing from the material principles thereof. It is not therefore desired to confine the invention to the exact form herein described and 65 shown, but it is wished to include all such as come properly within the scope claimed.

Having thus described the invention, what is claimed as new, is:—

The combination with a door frame in 70 cluding a lintel; of horizontal pivot arms supported beneath said lintel parallel thereto, a pair of tongs mounted on each of said arms and provided at their lower ends with upwardly converging jaws, springs normally holding said jaws together, a door mounted for vertical sliding movement beneath said tongs, and wedge members on the 75 upper edge of said door, said member being arranged to separate said jaws as the door 80 is raised whereby to permit engagement of said wedge members by said tongs.

In testimony whereof, I affix my signature, in the presence of two witnesses.

CLARK S. EATON.
